UNITED STATES PATENT OFFICE.

WILLIAM H. MUZZY, OF NEW YORK, N. Y., ASSIGNOR TO THE NATIONAL CASH REGISTER COMPANY, OF DAYTON, OHIO, A CORPORATION OF OHIO, (INCORPORATED IN 1906.)

CASH-REGISTER.

1,118,144.

Specification of Letters Patent. Patented Nov. 24, 1914.

Application filed October 14, 1908. Serial No. 457,705.

To all whom it may concern:

Be it known that I, WILLIAM H. MUZZY, a citizen of the United States, residing at New York, in the county of New York and State of New York, have invented certain new and useful Improvements in Cash-Registers, of which I declare the following to be a full, clear, and exact description.

This invention relates to improvements in cash registers and more particularly to machines of the type known as multiple totalizer registers, on which the accounts for different departments or different transactions such as cash, charge, received on account and paid out, may be kept. Heretofore the scope of usefulness of this class of machines has been confined to stores not having more than ten or twelve employees, or the same number of departments, on account of the limited number of totalizers which were possible in such machines. Establishments doing a credit business with a large number of customers are put to considerable inconvenience and in a number of instances to financial loss by mistakes in totalizing the accounts of different customers with the present systems of handling accounts.

It is the principal object of this invention to provide practically an unlimited number of detachable record retaining devices upon which may be entered mechanically the sales of the different attendants, departments or the credit accounts of the different customers, so that, at a glance, the totals of the different salesmen, departments or credit accounts may be seen.

Another object of this invention is to provide an improved form of record retaining device.

Another object of this invention is to provide a cheap totalizer which may be filed away as a record.

A further object is to provide a totalizer or accumulator having no moving parts.

With these and incidental objects in view, the invention consists in certain novel features of construction and combination of parts, the essential elements of which are set forth in appended claims and a preferred form of embodiment of which is hereinafter specifically described with reference to the drawings which accompany and form part of this specification.

Of said drawings: Figure 1 represents a perspective view of the machine embodying

the present invention with the lower portion broken away. Fig. 2 represents a central transverse section, partly broken away through the same. Fig. 3 represents an enlarged detail side elevation of the advancing and retracting mechanism for one of the punch actuated slides. Fig. 4 represents a rear elevation of the machine with the casing removed. Fig. 5 represents a horizontal section taken on the line 5—5 of Fig. 2, looking in the direction of the arrow. Fig. 6 represents a bottom plan view of the machine as shown in Fig. 2. Fig. 7 represents an enlarged detail rear elevation of the operating racks and coöperating mechanism. Fig. 8 represents a detail side elevation of the operating gearing. Fig. 9 represents a detail side elevation of one of the gears shown in Fig. 8. Fig. 10 represents a top plan view of the gear shown in Fig. 9. Fig. 11 represents a detail side elevation of another one of the gears shown in Fig. 8. Fig. 12 represents a top plan view of the gear shown in Fig. 11. Fig. 13 represents a detail side elevation of the operating gearing on the opposite side of the machine from that shown in Fig. 8. Fig. 14 represents a partial top plan view of the operating punches and the cams for shifting them laterally. Fig. 15 represents a partial top plan view of the sliding carriage and the drawer release mechanism controlled thereby. Fig. 16 represents a partial transverse section showing the independent cash receptacles and their releasing means. Fig. 17 represents a detail side elevation of the lock for the main operating shaft, which is controlled by the record retaining devices. Fig. 17a represents a view similar to Fig. 17 with the locking lever latched in an inoperative position. Fig. 18 represents an enlarged detail vertical section of a pair of the punches and the sliding carriage. Fig. 19 represents an enlarged detail side elevation of a part of the transfer mechanism. Fig. 20 represents an enlarged front elevation of the laterally movable punches. Fig. 21 represents an enlarged longitudinal section of one of the punch operating clutches. Fig. 22 represents an enlarged vertical section of the sliding carriage and escapement mechanism taken on line 22—22 of Fig. 23. Fig. 23 represents an enlarged detail vertical section of the sliding carriage escapement mechanism taken

on line 23—23 of Fig. 22. Fig. 24 represents an enlarged side elevation of one of the rack bars partly broken away. Fig. 25 represents an enlarged side elevation of one of the transfer slides. Fig. 26 represents an enlarged side elevation of one of the punch actuated slides. Fig. 27 represents a detail perspective view of the casing for holding the record card. Fig. 28 represents 10 a detail perspective view of one of the record cards. Fig. 29 represents a detail perspective view of the transfer levers and co-operating mechanism. Fig. 30 represents an enlarged side elevation of a part of the operating gearing. Fig. 31 represents a top plan view of the gearing shown in Fig. 30; and Fig. 32 represents a side elevation of the segment and co-operating gearing for returning the escapement carriage. 15

Generally described the invention comprises a series of amount determining devices in the form of adjustable levers which are moved along numerical scales formed upon the front of the cabinet until pointers carried by said levers are opposite the amount that is to be accounted. This movement of the levers sets the indicators through suitable intervening mechanism, to display the amount shown opposite the pointers and 20 also connect punch operating means to the operating mechanism of the machine. A record retaining device in the form of a rectangular card of paste-board or thin metal and bearing a plurality of groups of numerals is inclosed in a casing having perforations corresponding to the numerals upon the card, and placed upon a sliding carriage through an opening in the cabinet of the machine. This movement unlocks 25 the operating mechanism which is then started and first depresses a series of fingers into the outer perforations of the casing so as to control the lateral adjustment of the punching devices. An escapement mechanism is then operated to permit the carriage bearing the record retaining device to pass under the punches. These punches which represent cents, dimes, dollars and tens of dollars are arranged to be operated successively in order to simplify the transfer mechanism and are automatically disconnected from the operating mechanism after entering upon the retaining device the amount shown by the indicators. As the 30 carriage nears the end of its escapement movement, the casing carrying the record retaining device releases its corresponding cash drawer after which the operating mechanism returns the carriage and punching devices to their normal positions.

For convenience the detailed description of the parts has been divided and will be given under the various headings which follow:

65 *Amount determining devices.*—Adjustable

levers 1 fastened at their inner ends to segmental rack plates 2 are provided at their outer ends, which project through slots 3 formed in the cabinet 4, with knobs 5 and pointers 6, the latter playing over numerical scales formed upon the front of the cabinet. The segmental rack plates 2 are journaled upon a transverse shaft 7 and mesh with the lower ends of vertical rack bars 8, the upper ends of which mesh with pinions 9 secured to indicators 10. The bars 8 are provided at about their central portion with rack teeth 11, with which pinions 12 secured to totalizer wheels 13 engage when the registering frame 14 is lowered by an operation 80 of the machine as is shown and described in the patent granted to Thomas Carroll, February 9, 1904, No. 751,611. Projecting from each rack bar 8 are two pins 15, see Figs. 24, 25 and 26, which enter slots 16 in a slide 17 mounted adjacent to said bar. The pins 15 engage the upper ends of the slots 16 and thereby carry the slide with the bar 8 in its upward movement. As each bar 8 is lowered by the upward movement of its lever 1, a spring 18 will lower its companion slide 17. These slides are each provided at their rear edges with a V shaped notch 19 and ratchet teeth 20. Adjacent to each pair of slides 8—17 is a companion slide 21, also 95 provided with a V shaped notch 22 and ratchet teeth 23. Pivoted at the upper end of each slide 21 is an arm 24 which is provided with a triangular lug 25 and an anti-friction-roller 26. When the slides 17 and 100 21 are at zero, the notches 19 and 22 are in horizontal alinement with the lug 25 resting in said notches.

The rack bars 8 are guided by tie bars 27 and 28 extending laterally across the machine, while the slides 21 are guided at their upper ends by pins 29 projecting from the slides 17 into elongated slots 30 formed in said slides 21, and at their lower ends by hook projections 31 extending from the tie 110 bar 28, see Fig. 2. Attached to the rack bars 8 are blocks 8^a which are provided with V shaped notches 8^b while the slides 21 have similar notches 21^a with which spring pressed plungers 28^a engage to temporarily hold said bars and slides in any position to which they are adjusted. Mounted loosely upon a shaft 32, see Figs. 2, 4 and 7, are a plurality of levers 33 one for each of the arms 24, the upper ends of which are arranged to be drawn into contact with the rollers 26 carried by said arms by springs 34. The lower ends of said levers are arranged to engage with rollers 35 mounted upon the ends of irregularly shaped levers 36 which in turn are loosely mounted upon stub shafts 37 projecting from the side frames of the machine, see Figs. 2, 4 and 5. The ends of the levers 36 opposite the ends carrying the rollers 35 are provided with 125 130

downward projections 38, which carry beveled lugs 39 that engage with disks 40 provided with sleeves 41 which are splined upon transverse shafts 42 so as to allow a lateral movement of each disk and sleeve independent of its shaft but to compel the shaft to rotate with its sleeve and disk, see Fig. 21. Upon the operation of the levers 1 the rack bars 8 and the slides 17 will be elevated thereby camming the arms 24 rearwardly by means of the V shaped notches 19 cut in the rear edges of the slides 17. As the arms 24 move rearward, the roller 26 carried thereby will rock the upper ends of the levers 33 rearward and the lower ends downward and forward thereby camming the ends of the levers 36 carrying the rollers 35 in a direction so as to disengage the lugs 39, carried by the downward extensions 38 of the opposite ends of the levers, from the disks 40 to allow springs 43 to force the toothed sleeves 41 of the disks 40 into engagement with toothed sleeves 54 of the operating mechanism hereinafter described. The lower ends of the levers 33 with the exception of the dimes lever or the second from the left in Figs. 4 and 7 are so constructed that they cam the rollers 35 downward when they are rocked; but the dimes lever is provided with a beveled block 44, see Fig. 2, which engages with the underside of its roller 35 and raises the lever 36 to disconnect the opposite end from its disk 40 because of the dimes lever 36 being bent back from its pivotal point, as shown in Fig. 5. Springs 44^a which surround the stub shafts 37 normally hold the ends of the levers 36 bearing the beveled lugs 39 into contact with the disks 40 and are of sufficient strength to compress the springs 43 and thereby disconnect the sleeves 41 from the operating mechanism.

Record retaining devices.—By the phrase record retaining devices it is desired to cover broadly any form of mechanism, be it registering, printing, perforating or any other devices whereby a record of a single transaction or a plurality of transactions is retained for future reference. As shown in the drawings, these devices comprise a rectangular strip of cardboard or thin metal 45, see Fig. 28, bearing groups of numerals representing cents, dimes, dollars and tens of dollars reading from left to right in said figure and which is inserted in a cut out portion 46 formed in the bottom of a hinged casing 47 provided with perforations 48 at its top and bottom corresponding to the numerals upon the card 45 (Fig. 27). The top of the casing is equipped with a lock 49 which enters a recess 50 in the bottom of the casing when the parts are closed, to securely hold the parts together so as to prevent the removal of the card 45 after it is placed in the casing by the proprietor. The casing 47 is also provided at its ends with

holes 51 and at its forward side with a projection 52, the former for passing over pins 51^a on an escapement carriage, and the latter for releasing the corresponding cash receptacle as hereinafter described, the location of the projections being different upon the various casings. These record retaining devices are arranged to be placed upon the escapement carriage through an opening 4^a in the cabinet 4, see Fig. 1. It is to be understood that when it is desired to use the record retaining devices without having them control the opening of different cash receptacles, the projections 52 are located similarly upon all casings 47, and one receptacle would then be common to all of the cards.

The main shaft 32 of the machine is normally locked and is released upon the insertion within the machine of any one of the record retaining devices in the following manner: A bell crank lever 300 Figs. 17 and 17^a is pivotally mounted upon the left hand side frame and a roller 301 is mounted upon the lower extremity of the downwardly extending portion of said bell crank. Upon the insertion in the machine of any one of the casings 47 of the record retaining devices, it will contact with the roller 301 and rock the bell crank lever 300 into the position shown in Fig. 17^a, in which position it will be held by a pin 302, projecting from one arm of a small bell crank lever 303, pivoted to the side frame, springing under tab 304 of the rearwardly extending arm of bell crank 300. In this position the hook end 305 of the bell crank 300 is held out of engagement with a locking cam 306 secured to the shaft 32, thereby allowing the rotation of said shaft. As the shaft 32 nears the end of its rotation, an ear 307 fast thereto will engage with a pin 308 carried by the rearwardly extending arm of the bell crank against the tension of a coil bell crank 303 and rock said bell crank against the tension of a coil spring 309, so that the pin 302 will be carried from under the tab 304, which will allow the bell crank 300 to drop by gravity or be drawn by a suitable spring if desired into the position shown in full lines in Fig. 17, the record retaining device in the meantime having been advanced and retracted as hereinafter described. Upon withdrawing the casing 47 which is accomplished by tilting the front end so as to raise it above the pins 51^a and pulling it slightly forward and finally raising the rear end, the bell crank 300 will drop into the position shown by dotted lines in Fig. 17 with the hook end 305 into engagement with the locking cam 306, and thereby lock the shaft 32 from rotation until a record retaining device is again inserted. By latching the bell crank 300 in the position shown in Fig. 17^a, it will

not interfere with the advancing and retracting of the record casing 47.

Record entering means.—By this phrase, it is intended to cover broadly racks, segments, type carriers, perforating devices or any other means for entering a record of a transaction and the embodiment shown in the drawings comprises a series of punches for stamping out the numerals in the cards 45. As previously described, when the levers 1 are moved, the disks 40 and sleeves 41 mounted upon the shaft 42 are moved laterally by springs 43 so that the teeth 41^a of the sleeves 41 will engage with the teeth 54^a of the sleeves 54 forming a part of the operating mechanism. Upon the beginning of the movement of the operating mechanism, a yoke shaped frame 55 as hereinafter described will be rocked which will in turn 20 rock fingers 56, see Figs. 2, 5 and 18, by means of springs 57 interposed between the yoke 55 and the downward projections 58 of the fingers 56 so that the rearward ends of said fingers will enter the forward trans- 25 verse row of perforations 48 in the casing 47 with the exception of the extreme left hand one of each group for which there is no finger provided. If the card 45 has not been previously punched or if only part of 30 the numerals in a column have been perforated the fingers 56 will contact with the card 45 and any further movement of the yoke 55 will simply compress the springs 57, and carriages 59 carrying the punch 35 operating devices will be drawn to the left, see Fig. 20, by coil springs 60 until arrested by lugs 61, projecting downward from the carriages 59, contacting with stationary plates 62, see Figs. 5 and 14, in which position the punches are in alignment with the two left hand end columns of their respective groups, so that when the carriage bearing the record retaining devices, as herein-after described, passes under the punches 45 only these columns will be perforated. The words "rows" and "columns" are used throughout the specification and claims as designating the numerals or perforations running from side to side and from the 50 front to the back of the machine respectively. If there are perforations in the forward row of numerals of the card 45, the fingers 56 will pass through them and contact with upwardly extending projections 63 of centrally pivoted levers 64 secured to the underside of the escapement carriage 65. The rearward ends of these levers, which are slightly heavier than the forward ends so as to return them to normal position 55 after operating, are provided with upwardly extending projections 66 similar to the projections 63 so that when the latter are depressed, the projections 66 will be raised and in turn elevate inverted L shaped 60 locking blocks 67 located beneath the cents 65

sliding carriage, thereby carrying the horizontal portion of said blocks out of engagement with shoulders 68 of slots 69 formed in the forward ends of slides 70 and into the elongated portion of said slots. The released slides will be drawn forward by springs 71 until projections 72 formed thereon will pass into the path of the lug 61 projecting downwardly from the cents sliding punch carriage 59. 75

Pivoted upon a transverse rod 73 directly under the pivotal points of the levers 64, see Figs. 2, 6 and 18, are a plurality of levers 74 the forward ends of which are provided with laterally extending lugs 75 engaging the underside of the dimes and units of dollars groups of levers 64 while the rear ends have upward projections 76 which contact with locking blocks similar to the blocks 67 and release slides 70 for controlling the lateral movement of the carriages 59 carrying the punch operating devices for the dimes and units of dollars. The slides 70 are mounted upon plates 77 by transverse rods 78 which play in elongated slots 79 in the slides, and collars 80 surround the rods 78 to prevent any lateral displacement of said slides. Each carriage 59 comprises a base plate 81 and two vertical arms 82 extending from said base plate. One of the 85 shafts 42 passes through the upper ends of the arms 82 of each carriage while the base plate 81 is slidably mounted in grooves 83 of tie bars 84. Mounted between the vertical arms 82 of each carriage 59 is a pinion 85, 90 see Fig. 21, which is splined upon the shaft 42 so as to permit a lateral movement independent of the shaft, but to insure a rotary movement with the shaft. Pivoted upon each shaft 42 except the rearmost 95 one, are two bell crank levers 86, see Fig. 18, their horizontal arms extending in opposite directions and carrying at their extreme ends pinions 87 which are geared to pinions 85 by idlers 88 pivoted to the horizontal 100 arms 86. Secured to each pinion 87 is a disk 89 provided with a cam groove 90 into which enters a pin 91 projecting laterally from a punch 92, the latter being guided by a boss 93 projecting from the underside of 105 the base plate 81 of the carriage 59. The downwardly extending arms of the bell cranks 86 are bifurcated at their lower ends as at 94 so as to straddle a pin 95 projecting from one of the vertical arms 82 of each 110 punch carriage 59. The cut out portions of the bifurcated ends of the bell crank 86 are of greater width than the pin 95 so as to permit of a rocking movement of said bell cranks. A plurality of levers 96, one 115 for each pair of cam disks 89 and also one for the single disk which operates the tens of dollars punch 92, see Figs. 2, 4, and 7, are provided with laterally extending arms 97 the length of which are determined by the 120

greatest lateral movement given to their companion carriage 59. The cents cam disks 89 are in contact with the arms 97 of one of the levers 96 which is pivoted upon the 5 transverse shaft 7. (See Fig. 2). The free end of this lever has secured to it by a slot and pin connection 98 a vertical arm 99 the upper end of which carries a pawl 100, see Fig. 3, that engages the ratchet teeth of 10 the slide 21 controlled by the units of cents lever 1. The dimes cam disks 89 engage arms 97 of a vertically movable lever 96 which is guided by the tie bar 28 and the rotary shaft 32 and is provided with a similar 15 pawl 100 for engaging with dimes slide 21. The levers 96 for the dollars and the tens of dollars are pivoted upon a stub shaft 101 and are engaged by their respective cam disks 89 while at their forward free 20 ends they are provided with vertical arms and pawls for actuating the dollar and tens of dollars slides 21 similar to the arm 99 and the pawl 100 of the cents lever 96. The upper end of arms 99 and the lever 96 25 for the dimes slide are provided with elongated slots 102 through which the shaft 32 extends and acts as a guide for said arms and lever. Springs 103 hold the arms 97 of the levers 96 in contact with the disks 89.

30 As previously described the disks 40 and the sleeves 41 forming a part thereof are forced into engagement with sleeves 54, which form a part of the operating mechanism, upon the movement of the adjustable levers 1, so that upon the rotation of the sleeves 54, which is done successively as hereinafter described, the disks 40 will be rotated and being splined to the shafts 42, see Fig. 23, the latter will also be rotated.

40 The rotation of the shafts 42 will turn the pinions 85 splined thereon and the latter through the idlers 88 and the pinions 87 will rotate the cam disks 89. The card carriage 65 carrying the casing 47 containing the record card 45 will be moved inwardly step by step by mechanism herein-after described and if several of the numerals on the column have already been punched out, the punch 92 will pass through the perforations 48 and into similar perforations 104 in the carriage 65 and as the punch is withdrawn the escapement mechanism will be operated and the card carriage and its inclosed card drawn one space to the rear 45 by its spring 105. When the punch 92 encounters the cardboard 45 the latter will offer resistance enough to cam the disk 89 upward until one side of the bifurcated portion 94 of the bell crank 86 carrying the raised disk 89 contacts with the pin 95, see Fig. 18. The continued rotation of the disk will then cam the plunger 92 downward through the cardboard 45. This upward movement of the disk will rock 50 its lever 96 and through the arm 99 and pawl 100 will feed the slide 21 upward. This movement will be repeated until the V-shaped notches 19 and 22 are in horizontal alinement at which time the triangular lug 25 on the arm 24 will enter said notches 70 thereby permitting the spring 34 to draw the lower end of the lever 33 out of contact with the roller 35 projecting from one end of the lever 36 and at the same time allowing the spring 44^a coiled about the shaft 75 37, see Fig. 5, to force the opposite end of the lever 36 downwardly so as to cam the sleeve 41 of the disk 40 out of connection with the operating sleeve 54, stopping the rotation of the punch operating disk. By 80 reference to Fig. 5, it will be seen that the rear disk 89 of each pair is not in the same plane as the front disk, the object of which is to enable the completion of a registration in an adjoining column when it is begun 85 in a preceding column and its capacity has been reached. For instance, if five numerals have been punched out of the card 45, and it is desired to register nine more, the card carriage 65 will be moved rearwardly 90 and the front punch will stamp out the remaining five numerals in the column previously punched, and upon the punching out of the last numeral in the column a transfer mechanism to the next higher group 95 of numerals will be tripped as hereinafter described after which the punch operated by the rear disk will stamp out the remaining four numerals in the adjoining column. When the proper amount has been punched 100 out, the operating mechanism and the punch operating devices will be disconnected as previously described.

Operating mechanism.—The main shaft 32 may be rotated by a crank handle as 105 shown in Fig. 1, or by a motor if desired. This shaft is provided at both ends with gears 106 which mesh with idlers 107 that in turn mesh with gears 108 of the same size as the gears 106, see Figs. 8 and 13. Gears 110, 109, and 110 loosely mounted upon the ends of shafts 42 mesh with the gears 108 at their back and front respectively. At each side of the machine the gears 110 mesh with a similar gear 111 loosely mounted upon a stub shaft 112 and this gear in turn meshes with a gear 113 also loosely mounted upon one of the shafts 42. Gears 114, 115, 116 and 117 intermesh with each other and also with the gear 113 so that upon a complete 115 rotation of the shaft 32 the gears from 106 to 117 will be given a single rotation with the exception of the idlers 107 and 116, the former receiving not quite a full rotation while the latter receives a little more. Extending from the gear 109 on the right hand side of the machine is a sleeve 118, which has fastened to its outer end a large gear wheel 119, see Figs. 5, 8, 9 and 10. This wheel meshes with a similar wheel 120 120 125 130

mounted upon the casing of the machine, the latter wheel being provided with a cam groove 121 into which plays a pin 122 projecting from the lower end of an arm 123, the upper end of which is secured to one end of a sleeve 124 mounted upon a shaft 125. The other end of the sleeve 124 is fastened to one of the vertical arms 126 of the yoke shaped frame 55, see Fig. 5. It will thus be seen that upon the rotation of the wheel 120 the lower end of the arm 123 will be rocked forward thereby turning the sleeve 124 so as to rock the yoke frame 55 to depress the fingers 56 to control the lateral movement of the carriages carrying the punches as hereinbefore described. Just after the punch carriages have been shifted and the fingers 56 returned to normal position by the yoke frame 55, a segment 127 secured to the gear 108 on the right hand side of the machine engages a pinion 128 loosely mounted upon the front transverse shaft 42 and attached to one end of the forward operating sleeve 54 and rotates said pinion and sleeve a plurality of times. Adjacent to the right hand side frame and attached to the above mentioned sleeve 54 is a disk 129, see Figs. 22 and 23, equipped with a cam groove 130 in which plays a pin 131 projecting from a plunger 132 that is guided by a frame 133 attached to the side frame. A slot 134 cut in the plunger 132 receives a pin 135 projecting from an elbow lever 136 which is loosely pivoted upon a pin 137 extending from an arm 138 forming a part of the side frame. Mounted in the vertical arm of the elbow lever 136 is a pawl 139 the upper end of which is normally held in contact with the head of pin 137 by one of the teeth 140 of the escapement carriage 65 being in contact with the lower end of said pawl. A pawl 142 is connected to the elbow lever 136 by a short sleeve 143 and is normally out of engagement with the teeth 140. When the plunger 132 is cammed downwardly, the elbow lever 136 will be rocked thereby carrying the pawl 139 out of engagement with the teeth 140 and the pawl 142 into the path of said teeth. While the pawl 139 is out of engagement with the teeth it will be rocked into the position shown by dotted lines in Fig. 23, by a leaf spring 143^a which has one end attached to the outer end of a stud 144 that acts as a pivot for the pawl 139, while its other end extends between pins 145 projecting from the lower end of said pawl. As the plunger 132 is raised, the elbow lever 136 will be rocked by the lower portion of the slot 134 contacting with the pin 135 and thereby rock the pawl 139 into and the pawl 142 out of engagement with the teeth 140. As the pawl 142 passes out of engagement with the teeth the card carriage 65 will be drawn rearward by its spring 105 until arrested by the upper end of the pawl 139 contacting with the head of the pin 137. This escapement mechanism and the punches 92 are so timed, that just as the punches are withdrawn the card carriage 65 escapes. The pinion 128 is locked while the segment 127 is out of engagement therewith by a locking disk 146 attached to said pinion, which has a concave portion 147 that is engaged by an enlarged portion of a disk 148, secured to the segment 127, see Figs. 8, 9, 30 and 31. Just as the segment 127 engages the pinion 128, a reduced portion of the disk 148 presents itself to the disk 146 thereby allowing the rotation of the pinion 128 and the disk 146. As the segment passes out of engagement with the pinion, the enlarged portion of the disk 148 will engage the concave portion 147 of the disk and lock the same. The second operating sleeve 54 from the front is provided at its outer end with a pinion 149 similar to the pinion 128 and which is engaged by segment 150, secured to the gear 11 by a short sleeve 151, just after the pinion 128 has made its first revolution. This pinion and segment are provided with locking disks 152 and 153 respectively, similar to the disks 146 and 148. Gear 114, see Figs. 8, 11 and 12, is provided with a short sleeve 114^a to which is attached two segments 154 and 155 and locking disks 156 and 157. The segment 154 is arranged to engage a pinion 158 secured to the outer end of the sleeve 54 for operating the units of dollar punches while the segment 155 is adapted to engage pinion 159 secured to the outer end of the operating sleeve 54 of the tens of dollars punch, see Fig. 5. The locking disks 156 and 157 coact with disks 160 and 161 secured to the pinions 158 and 159 respectively, in a manner similar to the disks 146 and 148, as previously described. The segments 127, 150, 154 and 155 engage their respective pinions successively beginning with the cents so as to actuate the punches 92 for the different numeral groups in their proper order, as the casing 47 containing the record card 45 passes under said punches. Just after the segment 127 completes the operation of the escapement mechanism for the carriage 65, a segment 162 attached to the gear 109, see Figs. 5, 8, 9, 30, 31 and 32, will engage with a pinion 163 mounted upon a stub shaft 164 projecting from the side frame and give the same a complete revolution. This pinion meshes with a similar pinion 165 which has attached to it a gear wheel 166 that engages a pinion 167 carrying a gear wheel 168 and as the latter wheel is rotated its teeth will engage gear teeth 169 on the carriage 65 and return it to normal position. The pinion 163 is normally locked by a disk 163^a which is engaged by a disk 162^a attached to the side of the segment 162. These disks co-

operate with each other in a manner similar to the disks 146 and 148. The lower portion of wheel 168 is cut away as at 170 so as to allow the carriage 65 to escape. The above described gearing is so multiplied that a complete revolution of the pinion 163 will rotate the gear wheel 168 four times. The teeth 140 and 169 are mounted upon a forwardly extending arm 65^a of the carriage 65 which extends through the front of the cabinet 4, see Fig. 1, and protected by a table or platform 48 forming a part of said cabinet. As the carriage 65 is returned, its forward end will engage with the lower ends of pivoted plates 77^a, see Figs. 2 and 18, which are pivotally mounted in the plates 77 and rock same so that their upward ends which play in cut out portions 70^a of the slides 70 will engage the sides of the cut out portions of the released slides 70 and return them to normal position where they are related by the horizontal portions 69 of the blocks 67 engaging shoulders 68 of said slides.

Referring now to Figs. 13 and 14, that part of the operating mechanism for returning to normal position the laterally movable punch carriages will be described. Gears 109, 110 and 113 on the left hand side of the machine are equipped with beveled gears 171 which mesh with similar wheels 172 fastened to the upper ends of short vertical shafts 173 suitably mounted in the casing. These shafts have also fastened to them cams 174 which engage with pins 175 projecting downward from links 176 which are provided at their outer ends with elongated slots 177 through which extend the shafts 173, while at their inner ends they are pivoted to levers 177^a. These levers are pivoted at one end to the tie bars 84, while their free ends contact with one of the uprights 82 of their respective carriages 59, see Figs. 5 and 14, and hold said carriages in one of their extreme positions. Upon the beginning of the operation of the machine the fingers 56 are first depressed to determine the extent of lateral movement to be imparted to the punch carriages 59 as previously described, after which the cams 174 pass out of engagement with the pins 175 on the levers 176 thereby permitting the springs 60, see Fig. 20, to draw the carriages laterally until they are arrested by the lugs 61 coming into contact with the slides 62 and 70. After the punches 92 carried by the carriages 59 complete their work, the said carriages are returned to their normal positions by the cams 174 contacting with the pins 175 on the arms 176, see Figs. 13 and 14. The carriage 59 supporting the punch 92 for the tens of dollars column of numerals is limited to this single column and consequently does not require any shifting mechanism, it being understood, of course, that if it is desired to extend the capacity of

the record devices, the tens of dollars carriage may be equipped with the above described shifting mechanism. After a record has been entered and previous to the operation of the entering devices upon the succeeding operation of the machine it is essential that the slide or slides 21 be returned to their normal positions, for if they were not returned the same transaction could be indicated a number of times without entering it on a record retaining device more than once. The following means is provided to accomplish this result: Extending from each slide 21 is a roller 177, see Figs. 2 and 3, which is engaged by the forwardly extending arm of an elbow lever 178, that is pivoted at 179 to a forward extension 180 of the back frame of the machine. The downwardly projecting arm of each elbow lever 178 carries a roller 181 which is arranged to be engaged by a cam 182 secured to the rotary shaft 32. After the slides 21 have been ratcheted up by the pawl 100 as previously described, cams 183 secured to the shaft 32 will upon the very beginning of the next operation of the machine engage with pins 184 projecting from the lower ends of the pawls 100 and thereby rock the upper ends of said pawls out of engagement with the teeth 23 of the slides 21, after which the cams 182 will engage with the rollers 181 and force them rearwardly, while the forwardly extending arms of the elbow levers will be moved downwardly carrying with them the slides 21. All of this takes place before the operating sleeves 54 start to rotate, it being of course, understood that the pawls 100 are held out of engagement with the ratchets 23 while the slides 21 are being returned to normal position after which they spring back into engagement with said ratchets. While this machine has not been shown equipped with a flash to hide the indicators during an operation of the machine, it is to be understood that it may be provided with a suitable flash mechanism, such for instance as that shown in the aforesaid Carroll patent.

Transfer mechanism.—The form of mechanism herein shown broadly speaking is of that type in which the actuator for the 115 denomination of the record retaining devices in which the transfer is to be entered is given an additional movement. Referring now to Figs. 2, 18, 19 and 29, a detailed description of said mechanism will be given. As previously described the card carriage 65 has pivotally mounted on its underside a plurality of levers 64 one for each column of perforations 104, which are provided with noses 185 that are held in contact with a 125 transverse rod 186 by the rear ends of said levers being heavier than the forward ends. As the carriage 65 moves rearward and the zero or the tenth numeral of any column of any group is stamped out by its punch 92, 139

the forward end of the lever corresponding to the perforated column will be depressed by the punch 92 contacting with the upward projection 63 of said lever. When the forward ends of the levers 64 of each group are in a position to be actuated by their respective punches, the upward projections 66 on the rear ends of the levers are directly under a transverse arm 187 of a centrally pivoted pawl 188, which is provided at its upper end with a hook 189 that engages a notch 190 formed upon a vertical arm 191. The pawls 188 are pivoted to upward projections of the tie bars 84, the latter being provided with suitable slots 188^a through which the downward projections of said pawls extend. The transverse arms 187 of the pawls 188 extend across the entire group of their respective levers 64. The lower ends of the vertical arms 191 are guided by the tie bars 84 while their upper ends are enlarged and provided with elongated slots 192 through which pins 193 projecting from elbow levers 194 extend. These levers are pivoted upon the transverse shaft 7 and at their rear upper ends are provided with elongated slots 195 through which extends the shaft 32. The upper ends of the levers 194 are equipped with centrally pivoted pawls 196 which are adapted to engage with the ratchet teeth of the transfer slides 17. These pawls are normally held out of engagement with the teeth 20 by cams 197 secured to the rotary shaft 32 engaging with pins 198 projecting from the lower end of the pawls so as to allow the free up and down movement of the rack bars 8 to which the slides 17 are connected by slot and pin connection, previously described. The cams 197 pass out of engagement with the pins 198 to allow the pawls 196 to engage the teeth of the slides 17 before the punches 92 start to operate. Springs 199 have their ends connected to the levers 194 and hooks 200 secured to the tie bar 84 so as to actuate said levers when they are released by the pawls 188. It is, of course, to be understood that the different groups of levers 64 control the release of the levers 194 of the next higher denomination. It will be seen from the above description that when the tenth numeral of any column of the card 45 is stamped out, the slide 17 controlling the punches of the next higher denomination 55 will be advanced one step by the release of its lever 194 so that said punches will be given an additional reciprocation before the sleeves 41 and 54 for operating the punches are disconnected. At the beginning of the 60 succeeding operation of the machine, cams 201 attached to the main shaft 32 will engage rollers 202 projecting from the levers 194 and thereby cam the released lever or levers back to normal position so that the

vertical arms 191 connected to said levers 64 will be relatched by pawls 188, the upper ends of which are forced into engagement with the notches 190 of said arms by suitable springs (not shown). As the column of numerals for the tens of dollars is arranged to be perforated only when a transfer is made thereto only a single punch 92 is necessary.

Cash receptacles.—These receptacles are designed to take care of the receipts of the 75 different attendants so that in connection with the record retaining devices an absolute check is placed upon the operators of the machine, in that the amounts in the different cash receptacles must agree with the 80 amounts punched out of the corresponding record devices. As shown in Fig. 16, each cash receptacle 203 has fastened to the rear side a catch 204 with which hook pawls 205 pivoted to vertical plungers 206 are arranged to engage. These pawls are limited in their downward movement by pins 207 projecting from the plungers. Coil springs 208 surround the plungers and have their ends contacting with one of the partitions 209, which act as guides for the vertical movement of said plungers, and with pins 209^a carried by the plungers, thereby exerting a tendency to raise same. Elbow levers 210, see Figs. 15 and 16, of which 95 there is one for each plunger 206, are pivotally mounted upon a transverse shaft 211. The downward projection of each lever engages a shoulder 212 formed upon its respective plunger and holds it down against 100 the tension of its spring 208 with the pawl 205 carried thereby in engagement with its catch 204. The forward projecting arms of the elbow levers 210 are normally just above the plane of movement of the card 105 carriage 65 and their inclined ends 213 are arranged to be engaged by the projections 52 of the different casings 47 at the end of the rearward movement of the carriage 65 and thereby elevate the said ends so as to 110 rock the downward projecting ends out of engagement with the shoulders 212 of the plungers 206 and allow the same to be raised by their springs 208 until arrested by shoulders 214 formed thereon coming 115 into contact with one of the partitions 209. It is, of course, to be understood that the projections 52 of the different casings 47 are so located that no two of them will ever engage the same elbow lever 210. A transverse shaft 215, which has secured to its outer end gears 117 (see Figs. 8, 15, 16, and 17) is equipped with cams 216, one for each plunger 206, which are arranged so that at the end of the rotation of the shaft one of 120 said cams will engage the upper end of the released plunger and cam it downward to allow the downward projection of the cor-

responding lever 210 to engage the shoulder 212 of the plunger and lock the same in its normal position.

Having described the invention in detail a résumé of its operation will be given and the different parts referred to will be designated by their reference numerals. Assuming that the clerk indicated by "A" has sold goods amounting in value to \$1.59 and that his record card already indicates previous sales of \$9.55, he will place his record card 45 in the casing 47, and insert the casing and card through the opening 4* in casing 4 and upon the card carriage 65. He then 10 adjusts the handles 5 along their numerical scales until the pointers 6 appear opposite the numerals 1, 50 and 9, see Fig. 1, it being understood that the adjustment of the handles may take place before or after the 15 insertion of the record retaining devices. The movement of the handles 5 will rock the arms 24 which in turn will rock the levers 33 so as to disengage the lugs 39 carried by the downward projections 38 of levers 37 from the disks 40 carrying the sleeves 41 and allow the sleeves to be shifted by springs 43 to clutch the operating sleeves 54. By this movement of the handles 5, the slides 17 carried by rack bars 8 will be elevated a number of steps corresponding to the amount opposite the pointers 6. The shaft 32 is then rotated as previously described by any suitable mechanism, during the first part of the movement 20 of which the fingers 56 will be depressed into the openings 48 of the casing 47, but none of the zeros of the card 45 having been punched as shown in Fig. 28, the said card will offer resistance enough so as to allow 25 the compressing of the springs 57 by the yoke 55, after which the fingers are withdrawn and the cams 174, Fig. 14, pass out of engagement with the pins 175 projecting downwardly from the links 176, thereby 30 permitting the punch carriages 59 to be drawn to the left, Figs. 5 and 20, until arrested by the stationary slides 62. After the carriages 59 have been laterally adjusted, the segment 127, Fig. 8, will engage the 35 pinion 128 to operate the card carriage escapement mechanism and the cent punching devices. The inner row of perforations 104 is several spaces in front of the first punch 92, so as to permit of the ready insertion and removal of the casing 47. As the card carriage 65 escapes toward the rear, the first punch 92 will pass idly through the first five numerals of the left hand column of the cent group on account 40 of said card having been previously perforated, but as the punch passes through the sixth perforation 48 of the casing 47, it will contact with the card 45 which will offer enough resistance to raise disk 89 until one 45 side of the bifurcated portion 94 will con-

tact with the pin 95 projecting from one of the uprights 82 of the carriage 59 after which the continued rotation of the disk 89 will force the plunger through the card 45. This upright movement of the disk 89 will 50 rock the lever 96, which will raise the vertical arm 99 carrying the pawl 100, which will in turn ratchet the slide 21 upward. The above described movements will be continued for the seventh, eighth, ninth and tenth numerals of the first column after 55 which the rear punch 92 of the cent operating devices will contact with and punch out the first numeral of the second column, then the second, third and fourth numerals of 60 said column, which with the five numerals punched out of the first column make up the nine cents to be registered in the cent group.

It is to be understood that as each numeral is punched out the units slide 21 will be raised one space, so that when the ninth numeral has been stamped out, the V shaped notches 19 and 22, Figs. 25 and 26, of the slides 17 and 21 respectively will register, 65 thereby permitting the spring 34 to return the lever 33 and the arm 24 to normal position, and the spring 44 to rock the lever 36 to disengage the sleeve 41 from the operating sleeve 54. When the tenth numeral of 70 the preceding column is stamped out the punch 92 will contact with the projection 63 on the corresponding transfer lever 64 and raise the rear end of said lever, the upward projection 66 of which at this time is 75 directly under the arm 187 of the pawl 188 and rock said pawl so as to free the hook end 189 from the notch 190 of the vertical arm 191 which is connected at its upper end to the elbow lever 194, Figs. 18 and 19. 80 This lever will then be drawn upward by its spring 199 and advance the dime transfer slide 17 an additional step by the pawl 196, which has previously to the tripping of the pawl 188, sprung into engagement with 85 the ratchet teeth 20 of said slide. This additional movement of the slide is independent of its rack bar 8 and is permitted by the elongated slots 16 through which the pins 15 of the rack bar 8 project. It will be seen 90 from the above that the slide 21 of the dimes section will have to be ratcheted six notches before slides 17 and 21 register and thereby effect the transfer from the cents group. The slide 17 is held in its advance position 95 by the pawl 196 until the end of the operation of the machine when the cam 197 will engage the pin 198 and rock the pawl out of engagement with the teeth 20 which allows the spring 18 to draw the slide 17 back to 100 normal position with the top of the slots 16 contacting with the pins 15. The lever 194 is returned to normal position upon the beginning of the succeeding operation of the machine by cam 201 engaging pin 202 pro- 105

jecting from said lever. The remaining punching devices for the dimes, dollars and tens of dollars, will be operated successively and in a manner similar to the cents mechanism. After the slides 21 have been ratcheted up to register with the slides 17, they are returned to normal position upon the beginning of the succeeding operation of the machine by elbow levers 178, see Figs. 2 and 3, the forward ends of which contact with pins 177 projecting from said slides. The downward projections of these levers carry rollers 181 which are engaged by cams 182 secured to the main shaft 32, so that as said shaft starts to rotate the cams 182 will engage with rollers 181 and rock them rearward while the forward ends will move downwardly carrying the raised slides 21 therewith during which movement the pawls 100 will be held out of engagement with the ratchet teeth 23 by cams 183 secured to the shaft 32. After the proper amount has been stamped out of the card 45, the card carriage 65 will continue its movement toward the rear until the projection 52 of the casing 47 carried thereby rocks the corresponding lever 210 from engagement with the shoulder 212 of the plunger 206 and thereby releases clerk's A cash receptacle which will be thrown forward by its spring 217. The segment 162, Figs. 8, 9, 10, 30, 31 and 32, will then engage and rotate pinion 163 and through the pinions and gears 163, 164, 165, 166, 167 and 168 return the carriage 65 to its normal position against the tension of its springs 105. Simultaneously with the return of the card carriage 65 the laterally movable punch carriages 59 will also be returned by the cams 174 contacting with the rollers 175 projecting from the links 176, the latter being secured to the levers 177 which contact with the uprights 82 of said carriages. At the end of the operation of the machine the released plunger 206 will be returned to its lowermost position by a cam 216 secured to the shaft 215 and latched in this position by lever 210.

While the form of mechanism herein shown and described is admirably adapted to fulfil the objects primarily stated, it is to be understood that it is not intended to confine the invention to the one form of embodiment herein disclosed, for it is susceptible of embodiment in various forms, all coming within the scope of the claims which follow.

What is claimed is as follows:

1. In a machine of the class described, the combination with a record retaining device comprising a card, of a punching device positioned to perforate said card, and an amount determining element actuated by said punching device as the same perforates said card.

2. In a machine of the class described,

the combination with a record retaining device comprising a card, of means for moving said card step by step into the machine, a punching device positioned to perforate said card at each step thereof, and an amount determining element actuated by said punching device each time the same perforates said card.

3. In a machine of the class described, the combination with a record retaining device comprising a card, and a casing for the same having perforations, of a punching device positioned to pass through said casing perforations and perforate said card, means for moving said casing and card into the machine, and an amount determining element actuated by said punching device as the same perforates said card.

4. In a machine of the class described, the combination with a record retaining device comprising a card, of means for moving it step by step into the machine, a punching device differently positioned to perforate said card, and means for operating said punch in correspondence with each step by step movement of said card.

5. In a machine of the class described, the combination with a manipulative device and an element differentially moved thereby, of a record retaining device comprising a card, a punch automatically positioned to perforate said card when the punch is actuated, and devices controlled by said differential element for operating said punch.

6. In a machine of the class described, the combination with a manipulative device and an element differentially adjusted thereby, of a record retaining device comprising a card, a punch positioned to perforate said card, and means for operating said punch a number of times depending on said differential element.

7. In an accounting machine, the combination with a record card, of punches for entering records on said card, means for moving said punches laterally of the accounting machine, and means, controlled by the card, serving to govern the extent of said lateral movement of said punches.

8. In a machine of the class described, the combination with a manipulative device and an element differentially movable thereby, of a record retaining device comprising a card, a punch positioned to perforate said card, a device controlled by said differentially movable element for operating said punch, and means for advancing said card after each perforation thereof by said punch.

9. In a machine of the class described, the combination with a manipulative device and an element differentially set thereby, of a record retaining device comprising a card, a punch positioned to perforate said card, devices controlled by said differential element for actuating said punch, and means oper-

ated by said punch for disabling the punch actuating devices after the card has been perforated.

10. In a machine of the class described, the combination with a manipulative device and an element differentially set thereby, of a record retaining device comprising a card, a punch positioned to perforate said card, means controlled by said differential element for actuating said punch, devices for advancing said card after each operation thereof by said punch, and means actuated by said punch for disabling said punch actuating means after the perforation of the 15 card.

11. In a machine of the class described, the combination with a manipulative device and an element differentially set thereby, of a record retaining device comprising a card, a punch positioned to perforate said card, devices controlled by said differential element for actuating said punch, and means controlled by the card for bodily moving said punch as a whole.

25. 12. In a machine of the class described, the combination with a manipulative device and an element differentially positioned thereby, of a record retaining device comprising a card, a punch positioned to perforate said card, means controlled by said card for bodily moving said punch, as a whole, devices controlled by said differential element for actuating said punch, and means for moving said card after each perforation thereof by said punch, at an angle to the path of the punch.

30. 13. In an accounting machine, the combination with a carriage for a record card having a plurality of groups of numerals thereon, of means for punching out numerals in any group, means for moving the punching means in one direction over said card carriage, and means for moving said card carriage in a direction at right angles to the direction of movement of the punching means.

40. 14. In a machine of the class described, the combination with a record retaining device comprising a card, of a punch positioned to perforate said card, a manipulative device and an element adjusted thereby and having connections to control actuation of said punch, means for moving said punch bodily across said card, and connections having their movement determined by the perforations of said card and controlling said punch moving means.

45. 15. In a machine of the class described, the combination with a record retaining device comprising a card, of a punch positioned to perforate said card and means for actuating said punch, and devices controlled by the perforations in said card having connections for bodily moving said punch over said card.

50. 16. In a machine of the class described,

the combination with a record retaining device comprising a card, of a punch positioned to perforate said card, devices controlled by the perforations in said card and having connections for bodily moving said punch over said card, and means for moving said card after each perforation thereof, in a direction at an angle to the bodily punch movement.

55. 17. In an accounting machine, the combination with a driving member having a definite movement at each operation of the machine, of a driven member arranged to be given a variable movement by said driving member, a manipulative device for controlling the connection between said members and a spring operated element for disconnecting the said members.

60. 18. In an accounting machine, the combination with a manually operated element, of a driving member having a definite movement at each operation of the machine, a driven member arranged to be given a differential movement by said driving member, means controlled by the manually operated element for controlling the connection between said members, a movable element controlled by the driven member, and means controlled by the movable element for disconnecting said members.

65. 19. In an accounting machine, the combination with an adjustable slide having a notch, a second slide having a similar notch, a driving member, a driven member, and means controlled by said slides for connecting said members when the notches are out of alinement and for disconnecting them when the notches are in alinement.

70. 20. In a machine of the class described, the combination with a record retaining device comprising a card, and a casing for said card, of a punch positioned to perforate said card, devices for moving said casing and card after each perforation thereof by said punch, a manipulative device and an element adjusted by said device with connections controlled by said element for actuating said punch, and devices controlled by the perforations of said card for moving said punch bodily across said card.

75. 21. In an accounting mechanism, the combination with a driving member, of a driven member comprising punches and their operating mechanism, a manipulative device, a movable element controlled thereby, a second movable element controlled by the driven member, and means controlled by said movable elements for connecting and disconnecting the driving and driven members.

80. 22. In an accounting machine, the combination with a record retaining device, of a series of manipulative devices, means, controlled by said manipulative devices, for entering records on said retaining device,

devices for moving said means bodily across said retaining device, a series of fingers, controlled by said retaining device, and having connections to determine the extent 5 of said bodily movement of the record entering means.

23. In an accounting machine, the combination with a record retaining device, of means for entering records on said retaining device, devices for moving said entering means bodily across said retaining device, a series of fingers, controlled by said retaining device, and a series of slides, adjusted by said fingers, and constructed to determine 10 the extent of said bodily movement of the record entering means.

24. In an accounting machine, the combination with a record retaining device, of a series of manipulative devices, means, controlled by said manipulative devices, for entering records on said retaining device, devices for moving said entering means bodily across said retaining device, and means, controlled by the retaining device, constructed 20 to govern the extent of the bodily movement of said entering means.

25. In an accounting machine, the combination with a record retaining device, of a series of manipulative devices, punches, controlled by the manipulative devices, and constructed to enter records on said retaining device, means for moving said punches bodily across said retaining device, and devices, controlled by the retaining device, constructed to govern the extent of said 30 bodily punch movement.

26. In an accounting machine, the combination with a record retaining device, of means for entering records on said retaining device, devices for moving said entering means bodily across the record retaining device, and means, controlled by the retaining device, constructed to govern the extent of the bodily movement of said entering 40 means.

27. In an accounting machine, the combination with a record retaining device, of punches constructed to enter records on said retaining device, means for moving said punches bodily across said retaining device, and means, controlled by the retaining device, constructed to govern the extent of the bodily movement of said punches. 50

28. In an accounting machine, the combination with a record retaining device comprising a card, of means for entering records on said card, devices for bodily moving said entering means across said card, and means, controlled by said card, constructed to govern the extent of bodily movement of said entering means. 60

29. In an accounting machine, the combination with a record retaining device, of means for entering records on said retaining device, devices for moving said entering 65

means bodily across said record retaining device, a series of fingers, constructed to engage said retaining device, a series of levers operated by said fingers, and a series of slides controlled by said levers, and constructed to govern the extent of the bodily movement of said entering means. 70

30. In an accounting machine, the combination with a record retaining device having denominations of different value, of a plurality of actuators for entering upon the retaining device amounts of different denominations, controlling means for said actuators and means controlled by an actuator of a lower denomination for advancing the controlling means of the next higher actuator 75 one step so as to give the latter an additional movement to transfer the amount actuated in the lower to the higher denomination.

31. In an accounting machine, the combination with a record card divided into denominations of different value, of a plurality of actuators for entering upon the card amounts of different denominations, and means controlled by an actuator of a lower 80 denomination for giving the next higher actuator an additional movement to transfer the amount entered on the lower to the higher denomination. 85

32. In an accounting machine, the combination with a record card divided into denominations of different value, of a plurality of actuators for entering upon the card amounts of different denominations, and means for transferring to a higher from a 90 lower denomination whenever the amount entered in the latter equals a unit of the higher denomination. 95

33. In an accounting machine, the combination with a record card divided into denominations of different value, of a plurality of actuators for entering upon the card amounts of different denominations, manipulative devices for controlling the actuators, and means for transferring to a higher from a 100 lower denomination whenever the amount entered in the latter equals a unit of the higher denomination. 105

34. In an accounting machine, the combination with a record card having a plurality of groups of numerals, each being of a different denominational value; of a plurality of punches for stamping out amounts of different denominations, manipulative devices for controlling the punches, and means for transferring to a higher from a lower denomination whenever the amount stamped out in the latter equals a unit of the higher denomination. 115

35. In an accounting machine, the combination with a record card having a plurality of groups of numerals, each group being of a different denominational value, of a plurality of punches for stamping out amount 125 in the different groups, and means controlled 130

- by a punch of a lower group for giving the next higher punch an additional movement to transfer the amount stamped out of the lower to the higher group.
- 5 36. In an accounting machine, the combination with a record card having a plurality of groups of numerals, each group being of a different denominational value, of a plurality of punches for stamping out amounts 70 in the different groups, means for controlling the punches, a series of levers for actuating the punch controlled means, and means controlled by a punch of a lower group for actuating the punch controlled means through 75 10 its lever of higher denominational group so as to transfer the amount out of the lower to the higher group.
37. In a machine of the class described, the combination with a record retaining device having different denominational values, of means for entering a record upon said device, the said means being bodily movable, means for transferring from one denomination to the next higher, and combined means 80 20 for controlling the bodily movement of the entering means and the operation of the transfer means.
38. In a machine of the class described, the combination with a record card divided 85 30 into different denominational values, of punches for entering a record upon said card, the said punches being bodily movable, means for transferring from one denomination to the next higher, and combined means 90 35 for controlling the bodily movement of the punches and the operation of the transfer means.
39. In an accounting machine, the combination with a record retaining device constructed to accumulate the total of a plurality of entries made thereon, of a normally locked cash receptacle, and means controlled by the record retaining device for unlocking 95 the cash receptacle.
40. In an accounting machine, the combination with a bodily movable record retaining device constructed to accumulate the total of a plurality of entries made thereon, of a normally locked cash receptacle, and means controlled by the record retaining device for unlocking the cash receptacle.
41. The combination with a cash receptacle, of locking means for said receptacle, means for displacing said locking means, and means for positively returning the locking means to normal position.
42. The combination with a cash receptacle, of a spring operated locking plunger for said receptacle, a lever for holding the plunger in a locking position against the tension of its spring, and means for operating the lever to release the plunger.
43. The combination with a cash receptacle, of a spring operated locking plunger for said receptacle, a lever for holding the 100 105 110 115 120 125 130 plunger in a locking position against the tension of its spring, and means for operating the lever to release the plunger.
44. In an accounting machine, the combination with an operating mechanism, and means normally preventing actuation of said operating mechanism, of a record retaining device constructed to disable said preventing means, and devices, controlled by said operating mechanism, and constructed to move said retaining device bodily, whereby a record may be entered on said retaining device.
45. In an accounting machine, the combination with an operating mechanism, and means normally locking the same, of a record retaining device constructed to release said locking means, and devices, controlled by said operating mechanism, and constructed to move said retaining device bodily, whereby a record may be entered on said retaining device.
46. In a machine of the class described, the combination with a manipulative device and an element differentially adjusted thereby, of a record retaining device, a punch for entering records on said retaining device, connections controlled by said differential element for actuating said punch, and a second differential element operated by each record entering actuation of said punch, said second element being constructed to cause disabling of said punch actuating connections after the record has been entered on said retaining device.
47. In a machine of the class described, the combination with a manipulative device and a slide differentially adjusted thereby, of a record retaining device comprising a card, a punch positioned to perforate said card, and connections for actuating said punch, means controlled by said slide for rendering said connections effective, a second slide actuated by each perforating actuation of said punch, said second slide being constructed to disable said punch actuating connections after the record has been entered in said retaining device.
48. In a machine of the class described, the combination with a record retaining device comprising a card, of a punch for perforating said card, a manipulative device and connections controlled thereby for actuating said punch a plurality of times, means for moving said punch bodily, and fingers positioned to pass through perforations in said card and having connections to limit variably the movement of said punch by its moving means.
49. In a machine of the class described, the combination with a record retaining device comprising a card, of a punch positioned to perforate said card, a manipula-

5. In a machine of the class described, retaining devices, of a corresponding number of normally inaccessible cash receptacles, and means controlled by each of the record retaining devices for rendering its corresponding receptacle accessible. 70
10. In a machine of the class described, the combination with a record retaining device comprising a card, of a punch positioned to perforate said card, devices for controlling the operations of said punch, a spring for moving said punch bodily, fingers positioned to pass through perforations in said card, and connections controlled by said fingers for actuating said obstructing slides. 75
15. In a machine of the class described, the combination with a record retaining device comprising a card, of a punch positioned to perforate said card, devices for controlling the operations of said punch, a spring for moving said punch bodily, fingers positioned to pass through perforations in said card, and connections controlled by said fingers for actuating said obstructing slides. 80
20. In a machine of the class described, the combination with a record retaining device comprising a card, of a punch positioned to perforate said card, a carriage on which said punch is mounted, a manipulative device and connections controlled thereby for actuating said punch a plurality of times, means for moving said punch carriage bodily, a plurality of slides for obstructing the bodily movement of said carriage at variable points, feeling fingers positioned to pass through perforations in said card, and connections controlled by said fingers for actuating said obstructing slides. 85
25. In a machine of the class described, the combination with a record retaining device comprising a card of means for moving said card step by step into the machine, a punch positioned to perforate said card, a manipulative device, means for actuating said punch at each step of movement of the 90
30. In a machine of the class described, the combination with a record retaining device comprising a card of means for moving said card step by step into the machine, a punch positioned to perforate said card, a manipulative device, means for actuating said punch at each step of movement of the 95
35. In a machine of the class described, the combination with a record retaining device comprising a card of means for moving said card step by step into the machine, a punch positioned to perforate said card, a manipulative device, means for actuating said punch at each step of movement of the 100
40. In a machine of the class described, the combination with a record retaining device comprising a card of means for moving said card step by step into the machine, a punch positioned to perforate said card, a manipulative device, means for actuating said punch at each step of movement of the 105
45. In a machine of the class described, the combination with a record retaining device comprising a card of means for moving said card step by step into the machine, a punch positioned to perforate said card, a manipulative device, means for actuating said punch at each step of movement of the 110
50. In a machine of the class described, the combination with a record retaining device comprising a card, of a punch positioned to perforate said card, actuating means for said punch, normally disconnected therefrom, a manipulative device and connections serving to connect said actuating means to said punch by movement of said manipulative device from normal zero position, an element operated by each perforating actuation of said punch, and constructed to permit disconnection of said 115
55. In a machine of the class described, the combination with a record retaining device comprising a card, of a punch positioned to perforate said card, actuating means for said punch, normally disconnected therefrom, a manipulative device and connections serving to connect said actuating means to said punch by movement of said manipulative device from normal zero position, an element operated by each perforating actuation of said punch, and constructed to permit disconnection of said 120
60. In a machine of the class described, the combination with a record retaining device comprising a card, of a punch positioned to perforate said card, actuating means for said punch, normally disconnected therefrom, a manipulative device and connections serving to connect said actuating means to said punch by movement of said manipulative device from normal zero position, an element operated by each perforating actuation of said punch, and constructed to permit disconnection of said 125
65. In an accounting machine, the combination with a plurality of detachable record retaining devices constructed to be moved bodily when attached to the machine, of a corresponding number of normally inaccessible cash receptacles, and means controlled by any one of the record retaining devices for rendering its corresponding receptacle accessible. 130
56. In an accounting machine, the combination with a record retaining device comprising a plurality of denominational groups, each group containing a plurality of numerical columns, of means for entering records in the columns of the various denominational groups, and means controlled by the record retaining device for establishing coöperative relation between the entering means and the proper columns of the denominational groups. 135
57. In an accounting machine, the combination with a record retaining device comprising a plurality of denominational groups, each group containing a plurality of numerical columns, of means for entering records in the retaining device by punching out numerals of the columns of said retaining device, and means controlled by the latter device for establishing coöperative relation between the entering means and the proper columns of the denominational groups. 140
58. In an accounting machine, the combination with a record retaining device comprising a plurality of denominational groups, each group containing a plurality of numerical columns, of means for entering records in the columns of the various denominational groups, and means controlled by the record retaining device for so positioning the entering means that the records will be entered in the proper columns of the retaining device. 145
59. In an accounting machine, the combination with a record retaining device constructed to accumulate the total of a plurality of entries made thereon, of means for entering the record on the retaining device, a normally locked cash receptacle, and means controlled by the record retaining device for unlocking the cash receptacle. 150
60. In an accounting machine, the combination with a bodily movable record retaining device constructed to accumulate the total of a plurality of entries made thereon, of a means for entering the record on said retaining device, a normally locked cash receptacle, and means controlled by the record retaining device for unlocking the cash receptacle. 155

61. In an accounting machine, the combination with a plurality of detachable record retaining devices, of a normally inaccessible cash receptacle for each record retaining device, and means carried by the record retaining device for rendering the corresponding receptacle accessible.

62. In an accounting machine, the combination with a plurality of detachable record retaining devices constructed to be moved bodily when attached to the machine, of a corresponding number of normally inaccessible receptacles, and means whereby the aforesaid bodily movement of a detachable device will render the corresponding receptacle accessible.

63. In an accounting machine, the combination with a plurality of normally inaccessible receptacles, of a plurality of detachable record retaining devices constructed to be moved bodily when attached to the machine, and an extension carried by each retaining device whereby said bodily movement will render the corresponding receptacle accessible.

64. In an accounting machine, the combination with a plurality of detachable record retaining devices, of a plurality of normally latched receptacles, and means carried by each retaining device for unlatching a certain one of the receptacles.

65. In an accounting machine, the combination with a plurality of normally latched cash drawers, of a plurality of detachable record retaining devices corresponding to the drawers, mechanism for entering records in the retaining devices, and means carried by the retaining devices whereby the entry of a record in any one device will unlatch the corresponding cash drawer.

66. In an accounting machine, the combination with a plurality of detachable record retaining devices, of means for entering records in said devices, a plurality of normally

inaccessible receptacles, and means controlled by the several retaining devices whereby an operation of the entering means to enter a record in any one of the retaining devices will render accessible the receptacle corresponding to said device.

67. In an accounting machine, the combination with a record entering mechanism, of a plurality of detachable record retaining devices arranged to be given an invariable movement when attached to the entering mechanism, a plurality of cash drawers, latches for said drawers, and means carried by each retaining device whereby its invariable movement will unlatch the corresponding cash drawer.

68. In an accounting machine, the combination with a plurality of detachable record retaining devices each constructed to accumulate the total of a plurality of entries made thereon, of differential mechanism for entering items on said devices, a plurality of normally inaccessible receptacles corresponding to the retaining devices, and means whereby the entry of an item in any one of the detachable devices by the differential mechanism will render the corresponding receptacle accessible.

69. In an accounting machine, the combination with an operating mechanism, of a normally effective lock for said mechanism, item entering devices actuated by the operating mechanism, a plurality of normally latched cash drawers and a plurality of detachable record retaining devices controlling the lock for the operating mechanism and the selective unlatching of the cash drawers.

In testimony whereof I affix my signature in the presence of two witnesses.

WILLIAM H. MUZZY.
